UNITED STATES PATENT OFFICE.

JOHN E. BUXTON, OF OWATONNA, MINNESOTA.

GRAIN-BINDER.

SPECIFICATION forming part of Letters Patent No. 269,004, dated December 12, 1882.

Application filed April 15, 1882. (Model.)

To all whom it may concern:

Be it known that I, JOHN E. BUXTON, a citizen of the United States, residing at Owatonna, in the county of Steele and State of Minnesota, have invented certain new and useful Improvements in Grain-Binders; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a perspective view from the left-hand side of the machine, the delivery end of the machine being considered for the present purposes the front. Fig. 2 is a perspective view from the right-hand side of the machine, the delivery end of the machine being considered for present purposes the front. Fig. 3 is a bottom plan of the machine. Figs. 4 and 5 are views of the knotter; Fig. 6, a detail in perspective to show the knotter and the twine-guide, the discharge-arm, and the retaining-arm.

This invention belongs to that class of devices known as grain-binders, and the novelties and particular points of invention and improvements will be now more fully set out and explained.

The device being in many particulars like that shown in my Patent No. 248,401, will in those particulars be now only described so far as is necessary to set out fully and clearly the construction and operation of the features or parts which are new and on which I wish to secure a patent.

In the accompanying drawings, A is any suitable frame to hold this machine, and B the floor of the binder. The main shaft by which motion is imparted to the parts of the machine which form the gavel and do the binding is shown at C; and D is the shaft on which are eccentrically fixed the disks e, carrying with a reciprocating motion the packer-arms F. The two shafts C and D are connected by a sprocket-chain, g, or in any other suitable way, and are driven by any convenient power. The disks e are so mounted on shaft D as to insure an alternately-reciprocating movement to packer-arms F, the outer or upper ends of each

of which embrace by a loop, f, said disks. An increased steadiness is given to these movements of said arms and packers by having their outer ends, f', placed in bearings in bar a, which is suitably connected with the main frame A. The forward ends of said packer-arms have a suitably-curved outline to be readily adapted to engage upon or behind the incoming grain-stalks, and by the reciprocating motion aforesaid push them forward and against the gavel-forming arm H near the front edge of the machine. The packer-arms F move in guides k, and thus precision of action is secured. The arm H is curved, and while the gavel is being formed projects up through the slot a' in the floor of the binder. The arm H is secured upon one end of the shaft I. This shaft is suitably mounted in bearings under the floor of the binder, and at its opposite end is connected by arm i and a suitable link, i', and arm i'' with the cam-wheel L on the right-hand side of the machine. When the binding of the gavel is finished the cam l' on the face of wheel L has come in contact with the pin i''' of arm i'', and thus the shaft I is rocked, and the arms X attached to it coming up through the binder-floor eject the gavel from the machine. Simultaneously with this the binder-arm is retracted. In the further rotation of cam-wheel L the cam l' passes the pin i''', and the latter comes inside the cam l. This cam, by reason of its peculiar shape, operates (just before wheel L has ceased to revolve) to give motion to the arm i'' and cause the shaft I to be rocked, and thus retract the arms X and also bring up arm H. The pin i''', when wheel L again starts to rotate, is carried along inside that part of said cam l which is concentric with the wheel, and the arm i'' is at rest and arm H held steady while the gavel is being made and tied.

The needle or cord arm M is attached to the shaft Q, which is actuated by means of the link q on the left-hand side of the machine connecting with the arm e on the end of shaft C. The lower end of this link q is slotted and works on a pin in the arm q' at end of shaft Q, and produces the necessary intermittent motion of the needle or cord arm.

On a spring, q'', is a stud, q^3, which, when the binder-arm is elevated, is pressed into a slot or indentation in arm q', and thus locks

the binder-arm shaft while the binder-arm is around the gavel, and the spur q^4 on link q in the downward movement of the link acts on the spring q' to release this stud from said 5 position at the desired moment.

The knotter R, having jaws r for the cord, is properly mounted in the machine by means of the socket 1 and strap 2, in which its shank is placed vertically to receive actuating motion 10 from the gear-teeth on wheels C^4 , fixed on shaft C and which gears with the pinion r' of said knotter.

It will be seen in Fig. 4 that the knotter is composed of three jaws—one upper and two 15 lower—and between the two lower jaws is pivoted the tongue r^2 , which is held closed by spring r^3 to retain the cord; or the knotter may have only two jaws, the lower one slotted for the reception of the tongue r^2 . The up- 20 wardly-extended part r^4 of this tongue will in the revolution of the knotter come at the proper time against a suitable cam, a^* , which lowers the tongue to allow the ends of the cord (held by the grasper N) to come between 25 it and the upper jaw, the tongue being immediately closed against the upper jaw by spring r^2 , and the cord ends are thus held till the loop is pulled off and the knot formed.

The cord-guide P consists of a pair of open 30 jaws or fingers, p , fixed on the end of the vertical shank p' , so as to come near the knotter. This shank has a square side, p^2 , against which the arm C' on shaft C strikes as the cord-arm comes up over the gavel. As the cord-arm M approaches in its forward movement, the guide is turned about one-quarter round by means 35 of that part of arm C' which is at right angles to the shaft C. This engages on the side p^2 and brings the guide under the knotter, the curved part of the arm C' bearing against one 40 of the square sides p^2 , holding it in that position during the completion of the knotting operation immediately after the curved part of C' has passed from contact with square p^2 until 45 the bent arm C^2 , fixed on the shaft C, comes against the spur p^3 on the shaft of the guide and turns the guide-jaws outward. At the same time the spur c^5 on the inside of the arm C^2 engages the pinion of the knotter, turning 50 it about one-quarter round in the same direction. Thus the cord is allowed to fall off the knotter and out of the jaws of the guide. The guide is now returned to its original position by means of the arm C^3 on shaft C, which 55 engages on the spur p^4 on the guide-shaft, and the guide is again ready for the cord of the new gavel. The forked end of the guide-arm x between the grasper and the knotter serves to guide the cord into the jaws of the knotter. 60 When the cord-arm M has come up and over the gavel and placed the cord in the slot n in the grasper N said grasper is retracted by the reciprocating movement derived through its connecting lever-arm Z' , actuated by a pin in its 65 opposite end playing in the cam-path of wheel Z, which wheel is fixed on the shaft C. This movement of the grasper serves to hold the

end of the cord against the face of the arm O, through a slot o , in which the grasper has reciprocating movement. While the end of the cord is thus held in slot n of the grasper, the cord-arm M is carried back to await the formation of another gavel. At its return the cord falls into the jaws p of the cord-guide P, which jaws are now turned so as to point on either 70 side of the returning arm M, and thus the cord is held in safe position while the grain-stalks are being packed against the arm H. When the cord has been placed in the holding slot n in the grasper N, the grasper is retracted by 75 the lever-arm Z' , actuated by a pin in its opposite end playing in the cam-path of wheel Z on shaft C. This movement of the grasper serves to hold the end of the cord against the face of arm O through a slot, o , in which the 80 grasper plays, as aforesaid. The cord is cut by the spring-knife n' on the side of the grasper opposite the holding part n , the cutting being done between the knife and part O.

The shaft D, which gives motion to the 90 packer-arms, is mounted in movable bearings d , and has a spring, u , against one side of each of said bearings. The stop d^2 will prevent too far rear motion of said bearings. These springs will not only act on said bearing to keep the 95 shaft D well toward the knotter, but, by reason of the arm V being pivoted to the right-hand bearing d below its pivot d^* , will operate to retract said arm at the proper moment. After the tied gavel has been thrown off the binder- 100 floor by the arms X, which are attached to and actuated by the shaft I, and at the proper moment, as the arm H retires, come up through slots in the binder-floor for this purpose, these arms retire and arm H is again brought above 105 the floor, and the new gavel formed against it by the operation of the packer-arms. During this operation of forming the gavel the latch-head v , on the end of the arm V, engaging on the spur w of the clutch, disengages the clutch 110 from the notches on the sprocket-wheel y , which is loosely mounted on shaft C, and this stops the motion of the cord-operating mechanism. When the packer-fingers press hard enough against the gavel, the shaft D, is forced back, 115 which movement causes the bearings d , to which the arm is pivoted, to swing, and this throws the latch-head v of said arm from between the sprocket-wheel y and the projection w on the clutch W, whereupon said clutch, forced by 120 the spring w^2 , engages with the sprocket-wheel y , over which the forward part of the endless chain g passes, its rear part passing over the sprocket-wheel y' on the shaft D, and thus the 125 cord-carrying mechanism is started into operation. To produce this alternate stopping and starting motion it will be seen that it is necessary to have the sprocket-wheel loose on the shaft, and the clutch W mounted thereon so that it cannot rotate without rotating the shaft, but yet have a sliding movement longitudinally thereon. Hence the shank of the clutch is slotted, as at w' , through which a pin on the shaft 130 C projects. When the clutch engages, as above,

with the notches on the sprocket-wheel y it will cause the cam-wheel L on the end of said shaft to turn and operate the arms H and X , as above set forth.

5 The supplemental sprocket-wheel y' , which comes under the chain g midway between the shafts C and D , works on an arm mounted in bearings y^2 , which arm is actuated by a spring, y^3 , for the purpose of keeping the same tension on the chain when the shaft D is moved back by the pressure of the packer-fingers on the gavel.

Having now described my invention, what I consider new, and desire to secure by Letters 15 Patent, is—

1. In a grain-binder and in combination with the actuating-shaft D , on which are mounted the eccentrics e , the packer-arms F , each having loop f and guide ends f' , and operating substantially as set forth.

2. In combination with the cord-arm M and the knotted R , constructed and operated as described, the cord-guide P , having fixed jaws p on its lower end, and shank p' , provided with square side p^2 and spurs p^3 and p^4 , arranged to be operated by the arms C' , C^2 , and C^3 , all substantially as shown and described.

3. In a knotted having its projecting end slotted or provided with jaws, r , a spring cord-retaining piece r^2 , having projecting end r^4 and combined with cam a^* , substantially as and for the purposes set forth.

4. In combination with the arm H , the packers F , and movable shaft D , the arm V , and clutch mechanism on the shaft C , substantially as and for the purposes set forth. 35

5. The combination of cord-arm M , knotted R , guide P , operating as described, guide x , and sliding grasper N , having spring-cutter n' , 40 all constructed and operated substantially as set forth.

6. In a grain-binder, the combination of the packer-arms F , eccentric e , shaft D , bearings d , and arm V , with sprocket-wheel y , clutch 45 W , and shaft C , substantially as described.

7. In a grain-binder, the packers F , mounted on a swinging or movable shaft, combined with sprocket-chain g , operating as described, and tension-wheel y , substantially as set forth. 50

8. In combination with the movable bearings d of the shaft D and arm V , the spring u , substantially as set forth.

9. The knotted R , having jaws r , and provided with tongue r^2 , pivoted in the lower jaws 55 and controlled by spring r^3 , substantially as described.

In testimony whereof I affix my signature in presence of two witnesses.

JOHN E. BUXTON.
